[57] CLAIM

The ornamental design for a telephone set, substantially as shown.

DESCRIPTION

FIG. 1 is a perspective view from the left front of a telephone set showing my new design, showing the phone supported on its mount;
FIG. 2 is a front elevational view thereof;
FIG. 3 is a left-side elevational view thereof;
FIG. 4 is a right-side elevational view thereof;
FIG. 5 is an elevational view showing one end thereof;
FIG. 6 is an elevational view showing the other end thereof;
FIG. 7 is a rear elevational view thereof;
FIG. 8 is a side by side plan view of the underside of the handset telephone, and of the top of its mount;
FIG. 9 is a view similar to FIG. 2 thereof of a component of the set;
FIG. 10 is a view similar to the FIG. 3 thereof of a component of the set;
FIG. 11 is a view similar to FIG. 4 thereof of a component of the set;
FIG. 12 is a view similar to FIG. 5 thereof of a component of the set;
FIG. 13 is a view similar to FIG. 6 thereof of a component of the set;
FIG. 14 is a view similar to FIG. 7 thereof of a component of the set.
The components of the telephone set shown in FIG. 1 are presented separately in FIGS. 8-14 for ease and convenience of illustration.
